UNITED STATES PATENT OFFICE.

STACY B. HASELTINE, OF CHICAGO, ILLINOIS, ASSIGNEE, BY MESNE ASSIGNMENTS,
TO W. H. MINER, INC., A CORPORATION OF DELAWARE.

SIDE BEARING.

Application filed August 13, 1923. Serial No. 657,019.

This invention relates to improvements in side bearings for railroad cars.

One object of the invention is to provide a simple, practical and relatively inexpensive roller bearing, especially adapted for railroad car side bearings, and wherein is employed a friction roller that is self-centering without the aid of springs or other parts likely to get out of order.

10 More specifically an object of the invention is to provide an anti-friction roller side bearing for railroad cars, of a true cylindrical anti-friction roller type wherein means including vertically movable weights is provided for returning the roller to central position.

20 A further object of the invention is to provide a novel construction of roller adapted for use in connection with anti-friction bearings, comprising an outer portion formed of a section of steel tubing, and a cast center.

25 A still further object of the invention is to provide a side bearing of the type indicated, including a housing provided with a hardened steel bottom bearing plate, and means for securing the plate within the housing.

30 Other objects and advantages of the invention will more clearly appear from the description and claims hereinafter following.

35 In the drawing, forming a part of this specification, Fig. 1, is a vertical, sectional view taken transversely through the ends of the body and truck bolsters of a car showing my improvements in connection therewith. Fig. 2 is a top plan view of the bearing shown in Fig. 1, said view being partly 40 broken away to better accommodate the figure to the sheet of the drawing. Fig. 3 is a vertical, sectional view taken substantially on the line 3—3 of Fig. 1. And Fig. 4, is a detailed side elevational view of a counter-weight used in connection with my improved side bearing.

45 In said drawing, 10 denotes the under side of a body bolster and 11 the upper side of an opposed truck bolster. The improved bearing is shown as applied to the truck bolster and comprises, broadly, a base casting or casing A; an anti-friction element B; counter weights C—C; a supporting stand D; and a wear plate E.

55 The base casting A is of substantially rec-

tangular outline, and has parallel, spaced side walls 12—12, end walls 13—13, and perforated corner lugs 14 extending laterally at right angles from the lower ends of the side walls by which the casting is riveted or otherwise secured to the bolster. The opposite end walls 13 have their upper end portions outwardly offset and the intermediate portions thereof curved outwardly and upwardly thereby presenting inner concave surfaces 15 corresponding in curvature to the periphery of the anti-friction element B. The offset portions of the walls 13 are joined to the main portion of the casing A, by side walls 16, and the side walls 12 at the upper ends thereof are provided with opposed inwardly extending flanges 17 downwardly curved at opposite ends and merging with the webs 16, thereby defining a rectangular opening 18 through which the upper portion of the anti-friction element B is adapted to project. The end walls 13 are inwardly offset adjacent the opposite side walls 12, as clearly shown in Figs. 1 and 2, thereby providing vertical guideways 19 at 80 opposite sides of the casing A adapted to accommodate and guide the counter weights C—C for vertical movement. The upper ends of the guideways 19 are closed by the overhanging flanges 17, which also function as means for limiting the upward movement of the counter weights C.

85 The anti-friction element B comprises a true cylindrical portion composed of a section of steel tubing 20 and a core of cast metal 21. Depending counter weight wings 22 are provided at opposite sides of the cylindrical portion of the anti-friction element, the wings 22 being cast integral with the core 21. The anti-friction element is formed by casting the core and wings to the section of tubing, thereby forming an integral bearing member having a steel bearing surface.

90 It will be evident, that by thus forming the roller partly of steel and partly of cast metal, a very strong, durable and efficient roller is provided which may be manufactured at a lower cost than the usual all steel rollers formed of sections of steel bars.

95 The wings 22 are of generally triangular outline, as clearly shown in Fig. 1, having curved lower ends 23, straight, upwardly converging side edges 24 and rounded upper end portions 25. The wings 22 are dis-

posed with the centers of gravity thereof at a point considerably below the axis of rotation of the roller, thereby acting as counter-balancing means to assist in returning the roller to central position. As clearly shown in Fig. 3, the flanges 17 of the housing over-hang the wings 22 and are adapted to engage with the rounded upper ends thereof to aid in retaining the roller within the casing A. Each of the wings 22 is provided with a laterally projecting cylindrical lug 26 adjacent its lower edge, centrally disposed between the opposite side edges thereof. The lugs 26 of the wings 22 are in axial alinement and are adapted to co-act with the vertically sliding weights C to raise the latter when the anti-friction element B is rolled to either side of its central position, the wings 22 acting as crank arms swinging the lugs upwardly.

The weights C are in the form of heavy, rectangular cast metal blocks. Each of the weights C, as best shown in Fig. 4 is provided with an opening 27 extending upwardly from the lower edge thereof, centrally between the opposed ends of the member C. Each of the openings 27 is of a width to loosely accommodate the corresponding lug 26 and is provided with a curved upper wall 28 forming a bearing surface adapted to co-act with the cylindrical bearing surface of the corresponding lug 26. The slight clearance between the lugs and the side walls of the recesses 27 in the plates C is provided to permit of slight lateral movement of the lugs during the rolling action of the anti-friction element B.

As herein shown, two weights C are employed, the same being arranged at opposite sides of the casting, one being disposed in each guideway 19. Each of the weights C is limited to vertical sliding movement by the opposite end walls of the corresponding guideway. It will also be noted that the overhanging flanges 17 serve to retain the weights C within the housing and act as stops to limit their upward movement.

The plate E on which the anti-friction element B rolls, is of rectangular outline, being of a width substantially equal to the width of the lower portion of the roller and having its opposite ends beveled as indicated at 29 and adapted to rest on correspondingly beveled surfaces of transverse ribs 30 projecting inwardly from the end walls 13 and spaced from the lower edges thereof. The plate also rests on the supporting stand D to which it is riveted.

The supporting stand D, as clearly shown in Fig. 3 corresponds in width to the plate E, and as shown in Fig. 1 is provided with transversely disposed flanges 31 adapted to engage underneath the ribs 30. It will be seen, that when the parts are assembled, the plate E and the support D are securely held

within the casing by engagement of the beveled ends of the plate and the flanges 31 with the ribs 30. As clearly shown in Fig. 2, the stand D and plate E are disposed centrally, crosswise of the member A with considerable clearance between the edges of the plate E and the inner faces of the adjacent side walls 12 to accommodate the lower portions of the wings 22 and the weights C. Furthermore, the combined stand and plate E is also formed so as to present the upper face or wear bearing surface of the plate E at a considerable elevation above the bottom proper of the member A and the upper surface of the truck bolster, so as to provide proper clearance for the wings 22 and lugs 26.

To facilitate the cleaning out of dirt and other foreign matter, which may accumulate within the casing A, the side walls 32 thereof may be cut away as indicated at 32-32.

In assembling the device the weights C and the anti-friction element B are first inserted through the bottom of the casing, then the plate E is placed in position by inserting the same into the casing while held at an angle to the horizontal, until the ribs 30 have been cleared, the plate then being seated in horizontal position on the ribs 30. The stand or support D is then placed in position and riveted to the plate, access to the rivets being had by moving the roller to either side.

The normal position of the parts is that shown by the full lines in Fig. 1, in which position the lower surface of the body bolster is slightly spaced above the anti-friction roller B. When the bearing is brought into action by a radial movement and relative approach of the body and truck bolsters and the element B is rolled to either side of central or normal position, as for instance, to the position indicated by the dotted lines in Fig. 1, the lugs 26 will revolve about the axis of the roller, swinging upwardly and raising the weights C. At the same time, the integral counter weight wings 22 will also be swung upwardly raising the center of gravity thereof and displacing it to one side of the axis of the anti-friction element. The limit of movement of the anti-friction element B is obtained when the latter engages against one of the correspondingly curved inner surfaces 15 of the casing A. When the pressure on the bearing is removed, the anti-friction element B will be returned to normal position under the influence of gravity due to the counter-balancing action of the wings 22 and the action of the weights C, which during their downward movement force the lugs 26 to swing downwardly. As the sliding counter weights are limited to vertical movement in the guides 19 and the lugs 26 are guided in

the openings 27 of the counter weights, bodily shifting movement of the roller is prevented at all times and its coming to rest always at the central position is assured. The 5 counter weights C therefore perform a double function in that they assist the return of the roller to normal position under the influence of gravity and also maintain the proper relation between the roller and the casing A at all 10 times.

I have herein shown and described what I now consider the preferred manner of carrying out the invention, but the same is merely illustrative and I contemplate all 15 changes and modifications that come within the scope of the claims appended hereto.

I claim:

1. In a side bearing, the combination with 20 a casing; of a roller mounted therein having a counterweight portion whose center of gravity is normally below the rotational axis of said roller and a vertically sliding weight co-acting with said roller to effect return of the latter to normal position.

2. In a side bearing, the combination with 25 a casing; of a roller within said casing; self-centering means carried by said roller; a sliding counter weight within said casing guided for vertical movement only; and co- 30 acting means on said roller and weight for maintaining a predetermined relation between said roller and casing.

3. In a side bearing, the combination with 35 a casing; of a roller within said casing, said roller being provided with lugs having their centers of gravity below the center of gravity of the roller proper; of a pair of sliding counter-weights within said casing, said

counter-weights being provided with guide-ways for receiving said lugs; and means for 40 guiding the counter weights for movement in a predetermined path.

4. In a side bearing, the combination with 45 a casing provided on the interior thereof with integral ribs; of a roller mounted within said casing; a wear plate for supporting the roller, said wear plate having its opposite ends engaging one side of said ribs; and a stand rigidly secured to said plate by members extending through the contacting portions of said plate and stand, said stand being provided with flanges engaging with said ribs on the sides opposite to those engaged by said plate whereby, the plate and stand are held permanently assembled with 50 said casing.

5. In a roller for side bearings, the combination with an outer steel jacket; of a core of cast metal; and counter weight members cast integral with said core. 60

6. In a side bearing, the combination with a casing; of a roller element mounted in said casing, said roller consisting of a body portion and a hardened steel bearing surface portion secured together by casting the 65 body portion within the bearing surface portion, said body portion having counter-weight members cast integrally with said core; and vertically movable weights co-acting with the counter-weight members of 70 said roller, said parts coacting to return said roller to centered position.

In witness that I claim the foregoing I have hereunto subscribed my name this 2nd day of August, 1923.

STACY B. HASELTINE.
